United States Patent Office.

PATRICK S. DEVLAN, OF HUDSON CITY, NEW JERSEY.

Letters Patent No. 77,012, dated April 21, 1868.

IMPROVED MATERIAL FOR JOURNAL-BOXES.

The Schedule referred to in these Letters Patent and making part of the same.

TO ALL WHOM IT MAY CONCERN:

Be it known that I, PATRICK S. DEVLAN, of Hudson City, in the county of Hudson, and State of New Jersey, have invented a new and useful Improvement in Anti-Friction Journal-Boxes, and material therefor; and I do hereby declare that the following is a full, clear, and exact description thereof, which will enable others skilled in the art to make and use the same, reference being had to the accompanying drawings, forming part of this specification.

Figure 1 is a top view of my improved journal-box.

Figure 2 is a detail cross-section of the same, taken through the line x x , fig. 1.

Figure 3 is a sectional view of a portion of the anti-friction material before being cut up to be put into the journal-box.

Similar letters of reference indicate corresponding parts.

My invention has for its object to furnish an improved anti-friction journal-box, which shall be so constructed and arranged that the anti-friction material or part of said box may be conveniently replaced, when worn, by fresh material; and it consists in the anti-friction material, and in the manner in which it is inserted in the journal-box, as hereinafter more fully described.

A is the journal-box, in the concave or friction-surface of which are formed chambers or cavities, of any desired number or size, and which may be square, round, or of any other desired form. B is the anti-friction material, which is formed by impregnating the fibres of paper, felt, cloth, leather, or other suitable vegetable or animal fibrous material with pulverized plumbago, soapstone, or other fine earthy matter, and fixing it by means of the silicate of soda, potash, or other strong size, in the manner hereinafter described. In case paper is used, I prefer to unite the anti-friction ingredients with it when in the form of pulp. The paper-stock is prepared in the usual way, and washed perfectly clean from all dirt or grit. Then, while the pulp is in the paper-engine, I put into it about twenty-five per cent. of pulverized plumbago, (graphite,) or about the same quantity of pulverized soapstone, (steatite,) or of any fine earthy matter. After it is thoroughly mixed with the paper-pulp, I add about twenty-five per cent. of silicate of soda, or potash, or any other strong size. The pulp thus prepared is then passed over the rollers in the same manner as when making ordinary paper or pasteboard. The material is then calendered between rollers to the required thickness.

In case cloth, felt, or leather is used as the base or foundation of the anti-friction material, I saturate the cloth, felt, or leather in a mixture formed by mixing plumbago, or soapstone, or other fine earthy matter with a solution of silicate of soda, or potash, or other strong size, in the proportions above described.

The material is then dried and calendered to the required thickness.

The anti-friction material is prepared for use by cutting the sheets into pieces or blocks b' , of a shape and size to fit into the chambers or cavities formed in the journal-box by means of dies or punches. The pieces or blocks b' thus prepared and cut out are placed in the chambers or cavities of the journal-box, and the box is ready for use. When worn, the blocks b' are readily removed, and replaced with new ones, making the journal-box very convenient and efficient, and enabling it to be kept in proper condition at trifling expense.

It should be observed that paper may also be impregnated with the anti-friction ingredients in the manner last described, but, in the case of paper, I prefer the manner of preparation first described.

I claim as new, and desire to secure by Letters Patent—

1. Forming the anti-friction material for lining journal-boxes, of the ingredients, in the manner, and by the means herein described, and cutting the same by dies or with punches into the required shape, as set forth.
2. The lining for journal-boxes composed of fibrous material impregnated with pulverized plumbago, soapstone, or other earthy matter fixed with a strong size, and rolled and cut by dies or punching into the required shape, substantially as herein shown and described.

The above specification of my invention signed by me, this 11th day of February, 1868.

PATRICK S. DEVLAN.
